CLAIM

The ornamental design for a suspension assembly for a vehicle, as shown and described.

DESCRIPTION

FIG. 1 is a perspective view of a suspension assembly for a vehicle.

FIG. 2 is a front elevation view of the suspension assembly for a vehicle of FIG. 1.

FIG. 3 is a rear elevation view of the suspension assembly for a vehicle of FIG. 1.

FIG. 4 is a top plan view of the suspension assembly for a vehicle of FIG. 1.

FIG. 5 is a bottom plan view of the suspension assembly for a vehicle of FIG. 1.

FIG. 6 is a cross-sectional view of the suspension assembly for a vehicle taken along line 6-6 of FIG. 4; and,

FIG. 7 is a cross-sectional view of the suspension assembly for a vehicle taken along line 7-7 of FIG. 4.

The broken lines in the drawings represent features of the suspension assembly for a vehicle that form no part of the claimed design.
